APPARATUS FOR FORMING CURVED SHEETS

Edmund B. Cairns, Naugatuck, Conn., assignor, by mesne assignments, to Cairns Corporation, New York, N. Y., a corporation of Delaware

Application July 27, 1938, Serial No. 221,473
In Great Britain August 3, 1937

4 Claims. (Cl. 153—53)

This invention relates to processes and apparatuses for imparting controlled longitudinal and transverse curvatures to sheets of metal, and relates particularly to metal rolling devices and processes whereby cooperating concave and convex rolls are utilized to impart a transverse curvature to a sheet of metal and a longitudinal curvature is produced by varying the angle at which the metal is fed into the rolls. The invention further relates to automatically controlled mechanisms for varying the angle at which the metal enters the roll, and includes control elements which may be pre-set to cause a predetermined curvature to be imparted to the sheets of metal.

Devices for bending sheets of metal with compound and intersecting curvatures are already known in the art. For example, my United States Patent No. 1,828,489, patented October 20, 1931, discloses a sheet bending machine consisting of a carriage for drawing a flat sheet of metal between a pair of opposed concave and convex rollers and during the drawing action tilting the rolls to exert longitudinal stresses which will cause the metal to be shaped and drawn into a compound curved sheet.

My United States Patent No. 1,820,936, patented September 1, 1931, discloses another type of device which includes curved tracks or racks, along which a pair of horizontal complementary concave and convex rolls may move to curve a sheet of metal both longitudinally and transversely. The curvature of the sheet is controlled by the curvature of the racks. Therefore, the racks must be replaced when it is desired to produce sheets having different curvatures.

The present invention has as its principal object the provision of devices and processes for imparting longitudinal and transverse curvatures to sheets of metal, whereby identically curved sheets may be produced in successive drawing operations and the curvature of the sheets may be varied as desired.

A further object of the invention is to produce a simplified metal rolling machine which is capable of producing greatly varied curvatures in sheets of material.

A still further object of the invention is to produce a simplified construction which is operable without vibration or chattering to produce smooth and regularly curved sheets of metal.

The objects of the invention have been attained by providing a device having a pair of cooperating concave and convex rollers arranged with their axes normal to a work bench, which

5 bears and supports the weight of the rollers. The rollers are adapted to be reciprocated longitudinally of the table, and may also be moved transversely of their path to form a longitudinal curvature in a sheet of material which is also carried by the work bench.

10 The mechanisms for guiding the rolls longitudinally of the work bench and for moving the rolls transversely of the bench are operatively associated through a pre-settable mechanism, whereby the transverse movement of the rolls may be varied with respect to the longitudinal movement to produce varying curvatures in the sheets of metal or to produce sheets of metal having gradually changing curves therein.

15 For a better understanding of the invention, reference may be had to the accompanying drawings, in which:

Figure 1 is a plan view of a typical form of 20 metal rolling device with the work bench partly broken away;

Figure 2 is a side view of the device disclosed in Figure 1;

Figure 3 is a sectional view taken on line 3—3 25 of Figure 2;

Figure 4 is a sectional view taken on line 4—4 of Figure 2;

Figure 5 is a sectional view of a switch forming 30 a part of the control mechanism for varying the curvature of sheets;

Figure 6 is a top plan view of a modified form 35 of a metal rolling device; and

Figure 7 is a diagrammatic showing of the electrical circuit for controlling the lateral displacement of the forming rolls.

The form of the invention illustrated in Figures 1 and 2 consists of a work or draw bench 10 upon which is supported a guide rail 12. The guide rail 12 is pivotally mounted at one end on a post 40 14 fixed to the draw bench and carries at the pivoted end a platform 16 upon which is mounted an electric motor 18. The electric motor 18 drives by means of suitable reduction gearing 20 a sprocket 22 rotatably mounted on the post 14, and a chain 24 for moving the forming mechanism 26. The guide rail 12, as best shown in Figure 3, is of generally I-shaped cross section, similar to a railroad rail, providing outwardly opening channels 28 and 30 in which the chain 24 is disposed. The end of the guide rail 12 opposite the post 14 is provided with a sprocket wheel 32 about which the chain 24 passes. Adjacent the sprocket 32 is a bracket 36 carrying an electric motor 38, which is provided with a drive gear 40 which meshes with an arcuate rack

42 on the draw bench 10. The motor 38 is preferably provided with a reduction gearing system, not shown, which causes the gear 40 to rotate slowly and move the right-hand end of the guide rail 12 along the rack 42.

The forming device 26 may suitably consist of a rectangular frame 44 which carries a concave roll 46 and a convex roll 48. The rolls 46 and 48 are provided with suitable shafts 50 and 52, respectively, which are journaled in the upper and lower horizontal walls of the frame 44. Frictional resistance to rotation of the rolls 46 and 48 may be reduced by interposing roller thrust bearings 54 between the ends of the rollers 46 and 48 and the adjacent surfaces of the frame 44. 10 15

The frame 44 and rollers 46 and 48 are guided along the guide rail 12 by means of rollers 56 and 58 disposed in recesses 60 and 62, respectively, in the lower portion of the frame 44. The rollers 56 and 58 engage the upper lateral edges 20 25 of the guide rail 12 and prevent a rotation of the frame 44 relative to the guide rail.

The entire weight of the forming mechanism 26 is supported on the draw bench 10 through the medium of anti-friction rolls 64, whereby the only stresses applied to the guide rail are those encountered due to shifting of the forming mechanism 26 relative to the draw bench 10. As the forming mechanism is extremely heavy, there is little tendency for it to vibrate or tilt 30 35 relative to the draw bench during a forming operation.

The device is provided with means for holding a sheet of metal under tension, so that it may be drawn out and curved both longitudinally and transversely by the forming rolls. The sheet holding and tensioning means may consist of a pair of arcuate jaw members 66 and 68, which are pivotally mounted by means of loops 70 on an extension 72 of the pivot post 14. The opposite end of a sheet of material may be gripped between an arcuately curved plate 74 pivotally mounted on a post 76 which is fixed to the draw bench 10 and a cooperating curved plate 78 which is bolted to the curved plate 74. It will be understood that the posts 72 and 76 may be braced to render them rigid enough to withstand the stresses to which they are subjected, without bending. One end of the sheet of metal, designated as 80, is threaded between the rolls 46 and 48, and its opposite ends then gripped between the arcuate plates 66, 68 and 74, 78. The curvature of the gripping plates 66, 68 and 74, 78 is substantially the same as the curvature of the rolls 46 and 48. 40 45 50 55

If the motor 38, only, is actuated, the forming mechanism 26 is drawn along the guide rail 12 imparting only a transverse curvature to the sheet of metal 80. When, however, the motor 38 is actuated to move the right-hand end of the draw bar 12, for example, in a clockwise direction, the rolls 46 and 48 are likewise moved transversely of the draw bench 10, stretching the sheet of metal 80 longitudinally and changing the angle at which the sheet of metal enters the bight between the forming rollers. By varying the lateral displacement of the forming mechanism 26, varying longitudinal curvatures are imparted to the sheet. These curvatures can be suitably varied by varying the speed at which the right-hand end of the guide rail 12 is moved along the arcuate rack 42, and also by varying the extent of displacement of the end of guide rail 12. 60 65 70 75

In order to control the device automatically to

impart a predetermined longitudinal curvature to the sheet of metal so that duplicate sheets of material may be produced, I have provided electrical control means for varying the speed and direction of operation of the motor 38. The motor 38, as well as the motor 18, may be of the three-phase induction type whereby by varying the voltage supplied to the motors their speed of operation may be varied. Adjacent the arcuate rack 42 I have placed a series of switch elements 82 provided with switch actuating arms 84, which are engaged by a shoe 86 carried on the outer end of the guide rail 12. The shoe 86, during its movement in an arcuate path with the guide rail, will contact a roller 88 carried on the switch actuating arm 84, as best shown in Figure 5, and will depress a contact arm 90 into engagement with another contact arm 92 carried by the switch 82, thereby closing a circuit which, as in a manner hereinafter described, shunts the circuit around a resistance to increase the speed of the motor.

A suitable circuit for controlling the motor 38 is disclosed in Figure 7. This circuit consists of the three-phase lead wires 94 leading from a source of current supply to the stator of the motor 38. A suitable reversing switch 96 is located in the lines 94 for reversing the direction of rotation of the motor. This switch 96 may be located where desired in the path of movement of the shoe 86 in order to reverse the direction of movement of the guide rail 12. The rotor of the motor 38 is connected through suitable leads 98 to a double throw switch 100, whereby the circuit may be completed either through a manually controlled resistance changing device 102, or through the automatically controlled circuit comprising leads 104. Each of the leads 104 is connected through three identical resistance grids 106, 108 and 110 to the source of current supply. The grids 106, 108 and 110 consist of a plurality of similar resistances of identical value connected in series through magnetic switches 112. At the beginning of a forming operation, the switches 112, in the form of the invention illustrated, are closed and the resistances are in the circuit. The magnetic switches are so controlled that upon passage of electricity through the electromagnets 114, the corresponding resistances are shunted out to reduce the total resistance of each of the grids, thereby increasing the speed of the motor 38. Each of the magnetic switches 112 is controlled by a switch 82 whereby, upon contact of the shoe 86 with the roller 88 to close the circuit through control switch 82, the corresponding resistance in each of the grids 106, 108 and 110 is cut out until all the switches 112 are open as shown in Fig. 7. A master switch 116 may also be connected in the circuit for controlling operation of the entire device. The resistances making up the grids are preferably selected to vary in equal stages the change in speed of operation of the motor from the desired minimum speed to the desired maximum speed. It will be seen that a proper spacing of the switches 82 along the arcuate rack 42 will enable the device to form many different longitudinal curvatures to sheets of material, and when once so located will render the duplication of curvatures a very simple matter.

In Figure 6 is illustrated another form of the invention which may consist of a draw bench 120 having guide rails 122 at its lateral longitudinal edges. At the left-hand of the draw bench 120 is fixed an electric motor 124 which through

suitable gearing 126 causes movement of chains 128 about sprockets 130 and 132 adjacent each of the guide rails 128. One pass of each chain 128 is connected to a carriage 134 which is slideable along and guided by the guide rails 122. The carriage 134 is provided with a central aperture 136 within which is mounted a metal forming device 138, substantially identical with the metal forming device 26 heretofore described. The carriage 134 also supports a motor 140 which through suitable reduction gearing 142 drives a threaded shaft 144 passing through a portion of the metal forming device 138. Operation of motor 140 will cause the metal forming device 138 to move transversely of the draw bench 120. In this construction, the motor 140 is connected through a circuit like that disclosed in Figure 7 to a series of switches 82, which are identical with the switches heretofore described. The switches 82 are disposed adjacent one guide rail 122 and are engaged by a shoe 146 to vary the speed of motor 140. The shoe 146 is carried at the end of the carriage 134. If desired, one of the switches 82 may be replaced by a reversing switch 96 in order to cause a complete reciprocatory movement of the metal forming device 138.

A sheet of metal may be supported on the draw bench 120 in the manner described in connection with the first described modification of the device, and upon longitudinal and transverse movement of the metal forming device 138 the sheet is shaped into a compound transversely and longitudinally curved body.

While I have described the metal forming devices 26 and 138 as consisting of a pair of complementary concave and convex rollers, it will be apparent that die members consisting of complementary curved fixed members may also be used for shaping the material. These die members may be similar halves of the rollers 46 and 48 disclosed in Figure 3; that is, of such shape as would be produced by severing the rollers 46 and 48 diametrically along their longitudinal axes.

In operation, a sheet of metal is threaded between the rolls of the forming devices 26 or 138 with the forming devices at the right-hand end of the guide rails. The ends of the sheets are bent transversely and clamped in the gripping devices 66, 68 and 74, 78. The motors 18 and 38 in Figures 1 to 5, or motors 124, 140 in Figure 6 are started drawing the forming devices along the guide rails. Operation of the lateral traversing motors 38 or 140 will cause displacement of the forming devices and the production of longitudinal and transverse curves in the sheet of metal. The longitudinal curvatures imparted to the sheets will, as before explained, be controlled by the transverse displacement of the forming device. During operation, the metal sheet will be stretched and worked to produce a change in shape and rearrangement of the crystalline structure of the metal. The crystalline rearrangement rigidifies and strengthens the sheet so that structures formed from the sheets are far stronger and more rigid than similar structures formed from flat sheets of the same thickness. It will be understood that the sheets may be subjected to a plurality of successive shaping passes of the forming devices, and that the final curvature of the sheet may be produced by steps rather than in one shaping pass of the forming device.

It will be understood that any suitable means may be provided for varying the spacing between the rollers or the die members to accommodate

sheets of material of different thicknesses, and that such adjusting means may be regulated to produce a narrower space at one end of the rollers than at the other end, thereby working the metal more at one edge of the sheet than the other end, imparting an arcuate bend to the sheet in addition to the longitudinal and transverse curvatures.

In connection with the working of certain types of metals, it may be of advantage to operate under relatively high temperature conditions. This condition might arise, for example, in working with certain light metals or alloys. In such case the rolls may be conveniently heated internally by hot oil or steam which may be circulated by means of flexible connections attached to hollow shafts for the rolls as indicated by reference character 51. The rolls may be provided with hollow ducts or chambers through which the heating medium may effectively circulate. If additional heating is necessary, the frame 44 or the carriage 134 may carry a series of gas jets, fed from a manifold and to which gas or other combustion medium may be supplied with flexible connections preferably carried overhead to permit easy movement of the carriage. The several jets can be adjusted to heat the sheet uniformly across its face. If necessary, a series of jets can be carried on each side of the movable rolls and on the front and back also. Hoods or muffles may be provided to obtain more effective action. Another effective device is the use of electric resistance coils similarly placed across the face of the sheets. The amount of heating can then be closely controlled.

The above described embodiments of the invention should therefore be considered as illustrative only, and not as limiting the scope of the claims.

I claim:

1. A device for imparting a longitudinal and transverse curvature to a sheet of metal comprising means for restraining the ends of the sheet of metal against movement toward each other, a substantially horizontal support, complementary concave and convex forming elements mounted for movement longitudinally and transversely of the support with their axes perpendicular thereto and means for moving the forming elements transversely and longitudinally of the support, said last-named means comprising a guide rail for guiding the forming elements, means connecting one end of the guide rail to the support and means for moving the other end of the guide rail relatively to the support.

2. A device for imparting a longitudinal and transverse curvature to a sheet of metal comprising means for restraining the ends of the sheet of metal against movement toward each other, a substantially horizontal support, complementary concave and convex forming elements mounted for movement longitudinally and transversely of the support with their axes perpendicular thereto and means for moving the forming elements transversely and longitudinally of the support, said last-named means comprising a guide rail for guiding the forming elements, pivot means connecting one end of the guide rail to the support, a motor mounted on the guide rail adjacent the pivot means and a flexible member connected to the forming elements and actuated by the motor for moving said elements axially of the guide rail.

3. A device for imparting a longitudinal and transverse curvature to a sheet of metal com-

prising means for restraining the ends of the sheet of metal against movement toward each other, a substantially horizontal support, complementary concave and convex forming elements mounted for movement longitudinally and transversely of the support with their axes perpendicular thereto and means for moving the forming elements transversely and longitudinally of the support, said last-named means comprising guide means for the forming elements pivotally connected at one end to the support, a motor mounted on the free end of the guide means, an arcuate rack fixed with relation to the support adjacent the other end of the guide means and a gear driven by the motor meshing with the rack to move the free end of the guide means transversely of the support.

4. A device for imparting a longitudinal and

transverse curvature to a sheet of metal comprising means for restraining the ends of the sheet of metal against movement toward each other, a substantially horizontal support, complementary concave and convex forming elements mounted for movement longitudinally and transversely of the support with their axes perpendicular thereto and means for moving the forming elements transversely and longitudinally of the support, said last-named means comprising a plurality of switch elements, means associated with the forming elements for actuating said switches, an electric motor for moving the forming elements transversely of the support and an electric circuit for said motor controlled by said switches for varying the speed of operation of the motor.

EDMUND B. CAIRNS.
